UNITED STATES PATENT OFFICE.

WALTER W. NOBIENSKY, OF JANESVILLE, WISCONSIN.

STEAM BOARD.

Application filed January 27, 1923. Serial No. 615,209.

To all whom it may concern:

Be it known that I, WALTER W. NOBIENSKY, citizen of the United States, and resident of Janesville, in the county of Rock 5 and State of Wisconsin, have invented certain new and useful Improvements in Steam Boards; and I do hereby declare that the following is a full, clear, and exact description thereof.

10 This invention relates to steam boards and is particularly directed to steam boards adapted to be used in cleaning and pressing establishments.

Objects of this invention are to provide a 15 steam board which may be operated without using superheated steam, which is so constructed that the moisture will be separated from the steam and projected downwardly while the dry steam will rise and pass 20 through the top of the board and through superimposed goods, and to provide a steam board which is adapted for a variety of uses.

Further objects are to provide a steam 25 board which may be used either for treating goods prior to ironing, which may be used to remove wrinkles from goods and substantially duplicate the ironing process, which 30 may be used to remove residual odors from dry cleaned goods, and which is so constructed that the goods may be freely drawn over the top of the board or may be slid on to the overhanging position.

An embodiment of the invention is illustrated in the accompanying drawings in 35 which,

Figure 1 is a side elevation of the board with parts broken away to show the interior construction.

Figure 2 is a plan view with a portion of 40 the top broken away.

Figure 3 is a sectional view taken on the line 3—3 of Figure 2.

The steam board comprises a casing having a laterally arched top 1, provided with 45 a plurality of perforations 2. This top as may be seen from Figure 2, is relatively wide adjacent one end and tapers to a rounded relatively narrow end 3. The lower portion of the casing comprises converging 50 side walls 4 which together provide a trough-like bottom portion slanting downwardly from the larger top of the steam board. An end closure plate 5 is provided for the enlarged end of the casing. Adjacent the 55 lower portion of the casing a drain aperture

6 is formed and a drain pipe 7 extends therefrom,—such drain pipe being attached by any suitable means, as for example the internally threaded fitting 8, brazed, soldered, or otherwise securing the lower portion of the casing. Adjacent the outer or narrower portion of the casing the slanting walls of the bottom merge into a rounded portion 9, which is spaced a substantially uniform distance from the top 1, so as to 60 provide a material space between the top and the bottom portion adjacent the outer end of the casing.

A valve controlled steam pipe 10 enters the casing preferably through the top adjacent the larger end thereof, and branches into two substantially parallel pipes 11 and 12 of unequal length. The shorter pipe 11 terminates a considerable distance from the outer end of the casing, while the longer 70 pipe 12 extends a material distance into the narrower or contracted end of the casing. This arrangement of pipes is particularly advantageous as the greatest volume of 75 steam is supplied the casing where it is most needed, that is, adjacent its larger portion, while a smaller quantity of steam is supplied the casing adjacent its more contracted portion, or narrower end. These 80 pipes, it will be noted from Figure 3, are provided with a plurality of downwardly 85 opening apertures 13 which roughly parallel the inwardly converging side walls 4, of the bottom portion. This construction provides 90 downwardly projecting jets of steam which parallel the side walls and sweep condensed 95 material downwardly into the trough-like bottom portion. Also, any moisture carried by the steam will be thrown downwardly into the bottom trough-like portion, and 100 substantially dry steam will rise and pass outwardly through the apertures 2 in the top 1. The condensate drains downwardly towards the larger end of the casing and passes therefrom through the drain pipe 7.

The steam board may be conveniently supported by means of a pair of brackets 14, attached to the end plate 5 and provided with outwardly projecting feet 15, adapted 105 to be secured to the wall 16. At an intermediate point, a pedestal 17 is provided which rests upon the floor 18 and is attached to the underside of the casing. This construction has a neat and pleasing appearance and provides an outwardly pro- 110

jecting, overhanging, contracted end of the casing over which portions of the goods may be slipped if so desired.

In the operation of the device it is intended that the goods be either placed upon the top of the board or drawn thereacross and treated with the rising steam. This process of treatment will remove residual odors from dry cleaned goods and may be used also to prepare goods for subsequent ironing. Numerous other uses of the apparatus will suggest themselves and attention will therefore be called to only one more application. It frequently happens that with certain classes of goods such as crêpe de chine, for instance, ironing is undesirable while some renewing process is needed. This class of goods may be most readily treated by this apparatus by merely drawing them laterally across the board, thereby subjecting them to the action of steam without compressing and flattening them, as would be the case in the ordinary ironing process.

It will thus be seen that a steam board has been provided which is adapted to be employed in different capacities and to function in a manner applicable to a large variety of processes of treatment of goods. It will further be seen that a steam board has been provided which will renovate goods without the necessity of completely destroying their essential characteristics by ironing.

It is to be particularly noted that ordinary saturated steam may be employed for operating this steam board and that superheated steam is unnecessary, as the moisture carried by the steam is separated there-

from within the casing and blown downwardly thereafter, being led from the casing by means of the drawn pipe.

Throughout this description the term goods has been used to avoid needless enumerations. It is intended that this term shall be generic to clothes, goods in bulk, and other fabric structures.

Although one specific form of the invention has been described in considerable detail it is to be understood that the invention may take different forms, and that such invention, thereof, is to be limited only as set forth in the appended claim.

I claim:

A steam board comprising a casing having a transversely arched, longitudinally tapered, perforated top, and downwardly converging lower side walls slanting downwardly towards the larger end of said table, a drain pipe opening into said casing adjacent to its lowest portion, a steam pipe extending into said casing and branching into a pair of substantially parallel pipes of unequal length, the longer of such pipes extending into the narrower portion of said casing, said pipes having downwardly opening apertures whose axes roughly parallel the converging lower side walls of said casing, whereby moisture carried by the steam will be blown downwardly and dry steam will rise from the central portion of said casing and pass upwardly through said apertured top.

In testimony that I claim the foregoing I have hereunto set my hand at Janesville, in the county of Rock and State of Wisconsin.

WALTER W. NOBIENSKY.
